STOVEPIPE DAMPER FOR CHECK DRAFT
AIR ADMISSION

Edward A. Pound, Chicago, Ill.

Application May 7, 1945, Serial No. 592,411

5 Claims. (Cl. 126—293)

1

This invention relates to a furnace damper construction and more particularly to an improved damper valve assembly.

An object of this invention is to provide a damper valve which is economical to manufacture and which may be readily installed in existing furnace systems at a minimum of cost.

Another object of this invention is to provide an improved damper construction which when used in conjunction with existing furnace smoke pipes will greatly reduce the loss of heat through the chimney.

Another object of this invention is to provide a damper construction, which when connected with a furnace smoke pipe will enable fresh air to be drawn into the smoke pipe by the chimney draft thereby eliminating the necessity of withdrawing heated air from the building.

Yet another object of this invention is to provide a damper construction which will eliminate the need, in the regulating of a chimney draft, of having to withdraw heated air from the basement or other portions of the building being heated.

In accordance with the general features of this invention there is provided in a damper control structure for a furnace including a smoke pipe connected with a chimney, a pipe connecting a portion of the smoke pipe to the exterior of the building for supplying fresh air to the smoke pipe and including two abutting sections of the pipe and a damper valve interposed between the ends of the pipe sections for controlling the flow of fresh air into the smoke pipe to regulate the draft of the furnace.

A further feature of the invention relates to the provision of a damper valve which can be bodily inserted in a furnace pipe line with a minimum of changes therein, and which includes a housing ring, a valve disc therein and a shaft pivotally supporting the disc in the ring and with its ends extending beyond the periphery of the ring into opposite slots provided in the pipe.

Another feature relates to the manner in which the damper valve assembly of my invention is held at adjoining sections of pipe by a clamping ring lapping the abutting ends of the pipe on the exterior thereof.

Other objects and features of this invention will more fully appear from the following detailed description taken in connection with the accompanying drawings which illustrate a single embodiment thereof and in which

Figure 1 is a somewhat diagrammatic view,

2

partly in section, showing how my damper assembly may be used in conjunction with a furnace smoke pipe;

Figure 2 is a cross-sectional view through the abutting pipe housing my damper valve and drawn on an enlarged scale; and

Figure 3 is a cross-sectional view taken on the line III—III of Figure 2 looking in the direction indicated by the arrows.

10. As shown on the drawings:

I have designated generally by the reference character 10 a conventional furnace supported on a basement floor 11 of a building and below the first floor 12 of the building. A conventional smoke pipe 14 for the furnace extends through the building wall 13 and is in communication with the interior of a usual chimney 15.

In such a structure, it has heretofore been the practice to modify the draft by a damper which permits of the introduction of air from the basement in the smoke pipe 14. This, as pointed out before, is quite costly since it results in the chimney draft withdrawing substantial amounts of warm air from the building. I propose in lieu thereof to provide a separate pipe line 16 having one end in communication with the smoke pipe 14 and having its other end extending through an opening in the building wall 13 for communication with the exterior atmosphere. Thus fresh air can pass through the pipe 16 into the smoke pipe 14 in response to the desired draft conditions.

The control of the flow of fresh air through the pipe 16 in the smoke pipe 14 is effected by 35 a damper valve assembly embodying the features of my invention and designated generally by the reference character 18.

This damper valve assembly is disposed substantially at the junction of the abutting ends 40 of two pipe sections 16a and 16b comprising joints of the pipe line 16. It includes a ring 19 having a diameter such that it can be bodily inserted endwise in and tightly fitted within one of the pipe sections, such as the pipe section 16b. This 45 ring may be made of any suitable material, although I preferably propose to make it in the form of a die casting, and contemplate that it may be cast of white metal or the like.

The opposite faces of this cast ring 19 are 50 recessed at 20 and 21 to provide inclined valve seat shoulders 22—23 on opposite sides of the medial plane of the ring. These inclined shoulders 22—23 are so formed as to be in a common plane inclined slightly relative to the normal 55 plane of the ring. This arrangement is such that

a metal disc valve 24, when seated against the shoulders 22-23 and in closed position, is not at right angles to the pipe but is slightly inclined in the direction of the flow of air through the pipe 16. This disc may be made of any suitable material although I contemplate making it of galvanized sheet metal.

The disc 24 is bolted by means of screws or bolts 26 to a shaft 25 the movement of which will open or close the valve as the case may be. The ends 10 of the shaft 25 are journaled in the ring 19 and extend beyond the ring at both sides through the oppositely disposed slots 27 formed in the end section 16b.

Suitably secured to one of the exterior ends 15 of the shaft 25 is a weighted lever 28 having an adjustable weight 29 thereon. The free end of the lever is connected by means of a chain or rope 30, as shown in Figure 1, trained over suitable pulleys, to a regulating or operating device 31 which may be on the first floor of the building. By pulling on the chain 30 it is possible to regulate the position of the damper valve 24 and a further adjustment can be effected by varying the position of the weight 29 on the lever 28.

In accordance with the novel features of my invention, I employ a clamping metal band 32 for holding the two pipe sections 16a and 16b together in alignment and also for holding the ends of the shaft 25 in the bottoms of the opposite slots 27. That is to say, an edge of the band, as shown in dotted lines in Figure 2, engages the extremities of the shaft to press the same firmly against the bottoms of the slots 27-27. The ends of the bands, as is customary in such clamping bands, are offset and are detachably fastened together by means of a screw 33 as shown in Figure 3.

Now it is clear that a minimum amount of change in existing furnace smoke pipes as well as a minimum amount of labor is involved in the application of the damper valve assembly of my invention thereto.

First a hole must be cut in the smoke pipe 14 for receiving an end of the pipe line 16 and the wall 13 must be provided with a hole leading to the exterior of the building for receiving the other end of the pipe line.

I preferably apply my damper valve assembly to the junction of the adjoining ends of pipe sections 16a and 16b, as I can insert it there with a minimum amount of labor and parts. In fact, the only modification I have to make in the existing galvanized pipe 16b is to cut two diametrically opposite slots 27-27 in an end of the pipe. Then I slide the ends of the shaft 25 into the slots and position the pipe sections 16a and 16b in alignment. Thereafter I apply the clamping band 32 to the aligned ends of the pipe sections 16a and 16b and use that clamping ring, as indicated before, to hold the sections together and to also hold the ends of the shaft 25 tightly in position in the slots 27.

Thereafter the chain or rope 30 is connected to the damper lever 28 and to the manual regulator 31 so that the damper can be regulated in accordance with the requirements of the particular house being heated.

My invention thus enables the chimney draft to withdraw its requirement of air from the exterior of the building rather than taking warm air from the building.

I claim as my invention:

1. In a damper structure for a furnace including abutting pipe sections one of which has its ends slotted on opposite sides, a valve inserted in said slotted pipe end including a ring, a valve disc and a shaft for pivotally supporting the disc in the ring, said shaft having its extremities beyond the periphery of said ring extending into the slots and a clamping ring lapping the abutting ends of said pipe sections on the exterior thereof.
  2. In a damper structure for a furnace including abutting pipe sections one of which has its ends slotted on opposite sides, a valve inserted in said slotted pipe end including a ring, a valve disc and a shaft for pivotally supporting the disc in the ring, said shaft having its extremities beyond the periphery of said ring extending into the slots and a clamping ring lapping the abutting ends of said pipe sections on the exterior thereof, said clamping ring having an edge abutting the external ends of said shaft to retain the same in the ends of said slots.
  3. In a damper structure for a furnace including abutting pipe sections one of which has its 25 ends slotted on opposite sides, a valve inserted in said slotted pipe end including a ring, a valve disc and a shaft for pivotally supporting the disc in the ring, said shaft having its extremities beyond the periphery of said ring extending into the slots and a clamping ring lapping the abutting ends of said pipe sections on the exterior thereof, and a weighted operating lever connected to one of said shaft ends on the exterior of said pipe sections.
  4. In a damper structure for a furnace including abutting pipe sections one of which has its end slotted on opposite sides, a valve inserted in said slotted pipe end, including a housing ring, a valve disc therein and a shaft for pivotally supporting the disc in the ring, said shaft having its ends extending beyond the periphery of said housing ring and into the slots, and a clamping ring lapping the abutting ends of said pipe section on the exterior thereof, said housing ring comprising a casting with opposite faces recessed 45 to provide inclined valve seat shoulders disposed in a common plane inclined relative to the normal plane of the housing ring.
  5. In a damper structure for a furnace including aligned abutting pipe sections, one of which has its end slotted on opposite sides, a valve comprising a disc-like body portion insertable in said slotted pipe end, and diametrically opposed projecting shaft portions respectively extending 55 into said slots, and a clamping ring lapping the abutting ends of said pipe sections, said clamping ring having an edge abutting said shaft portions to retain the same in the ends of said slots.
